[57] CLAIM

The ornamental design for a record player, as shown and described.

DESCRIPTION

FIG. 1 is a front, top and right side perspective view of a record player showing my new design;

FIG. 2 is a top plan view;

FIG. 3 is a left side elevational view;

FIG. 4 is a front elevational view;

FIG. 5 is a rear elevational view; and

FIG. 6 is a bottom plan view thereof.

The regularly spaced, rectangular ornamentations on the outer-most vertical, cylindrical wall of the turntable are merely surface markings.

FIG. 1

FIG. 2

FIG. 3

FIG. 4

FIG. 5
